UNITED STATES PATENT OFFICE

134,130

DESIGN FOR A SLED

John H. Burr, New Richmond, Wis.

Application August 29, 1942, Serial No. 108,074

Term of patent 7 years

To all whom it may concern:

Be it known that I, John H. Burr, a citizen of the United States, residing at New Richmond, in the county of St. Croix and State of Wisconsin, have invented a new, original, and ornamental Design for a Sled, of which the following is a specification, reference being had to the accompanying drawing, forming a part thereof.

In the drawing:

Fig. 2 is a side elevation of the same;

Fig. 3 is a bottom perspective view of the same, and

Fig. 4 is a rear end view of the same.

I claim:

The ornamental design for a sled, as shown.

JOHN H. BURR.
